UNITED STATES PATENT OFFICE

2,352,946

LIFTING MECHANISM FOR PLOWS

William A. Doane, Waverly, N. Y.

Original application January 4, 1940, Serial No. 312,422. Divided and this application March 20, 1941, Serial No. 384,401

2 Claims. (Cl. 192—62)

This invention relates to a lifting mechanism associated with a wheel of a wheeled plow and constructed and arranged for adjustment in a novel manner so that the frame of the plow may be maintained in lowered, raised or intermediate height, regardless of the inclination of the land.

It is particularly aimed to provide a construction wherein the raising and lowering of the frame will be effected through movement of a wheel and wherein novel clutch means are provided to cause the raising or lowering movement and are associated with means to prevent damage to the parts through excessive movement in either direction.

The more specific objects and advantages will become apparent from a consideration of the description following taken in connection with accompanying drawings illustrating an operative embodiment.

In said drawings:

Figure 1 is a plan view of a reversible plow construction in connection with which the invention is employed;

Figure 2 is a horizontal section taken on the plane of line 2—2 of Figure 1;

Figure 3 is a fragmentary side elevation particularly showing the left hand wheel of the plow and the parts constituting the invention;

Figure 4 is a vertical section taken on the plane of line 4—4 of Figure 3;

Figure 5 is a detail section taken on the plane of line 5—5 of Figure 4;

Figure 6 is a front elevation of the outside drum, and

Figure 7 is a fragmentary elevation of the outside drum and associated parts.

Referring specifically to the drawings wherein reference characters designated like or similar parts, the machine disclosed is a two way reversible tractor plow like that disclosed in my Patent 2,239,596, issued April 22, 1941, and which it is to be understood is shown by way of example only to facilitate an understanding of the invention. The present application constitutes a division of the said patent. Said two way reversible tractor plow as a whole is designated 10 and has a skeleton metallic frame as at 11 supported by ground wheels at 12 and 13, mounted and operable so that they may be adjusted to operate at different heights to maintain the plows in raised and lowered positions and to operate at different heights to maintain the frame level with respect to the ground. The plows are shown at 25. Coulters 110 are provided in advance of the

plows, being journaled on the lower ends of standards 112.

The wheel 13 and its mounting constitute no part of the present invention herein claimed. However, it is adjustably mounted like and corresponds to the wheel 11 in the aforesaid allowed application on a transverse shaft or rod 62 which is adapted to be rocked in either direction for adjustment and normally to be rigidly secured to the frame 11. Such rod 62 has a lever 63 and co-acting lock mechanism associated therewith, which is operable to rock the shaft 62 and secure it at the different angles of adjustment.

The previously mentioned wheel 12 has a rim 69, spokes 70 and a hub 71. Hub 71 is journaled on an axle 72 having an upwardly extending crank arm 73 which is pivotally suspended by a pin 74 on an arm 75 depending from a lever 76 pivoted at 77 to the frame 10 and adapted to be secured thereto at various adjustments. An annular drum 78 is welded or otherwise fastened at its inner edge to the spokes 70 concentrically of the wheel 12 and it has longitudinal corrugations or teeth 79 on the inner surface thereof.

An outer drum 80 surrounds the drum 78, having an outer wall or disk 81 which is pinned or otherwise rigidly fastened to the axle 72. Within the drum 78 is a latch member 83 which is pivoted at 84 to an arm 84a fixed on axle 72, to which latch member and arm a contractile coil spring is fastened to urge a pin 86 journaled on the latch 83 into engagement with adjacent teeth 79, to latch or lock the drums 78 and 80 together whereby turning of wheel 12 will also turn drum 80. Said pin 86 is rigid on an arcuate lever 87 pivoted at 88 on the exterior of drum 80 and extends through an enlarged slot 89 in disk 81. Said lever 87 has enlarged ends 90 and 91 located adjacent notches 90a and 91a in the periphery of disk 81.

The said transverse shaft or rod 62 has a depending arm or crank 94 which is slidably engaged in a bearing 95, fastened to a cap 92 which is loosely supported on axle 72 and an outwardly extending annular flange 93 on disk 81. A collar 96 surrounds the crank 94 and a bell crank lever 97 is pivoted thereto at 98 to one end of which a link 99 is pivoted and which in turn is pivoted to a sliding element 100 mounted on the crank 94. Such element 100 has an arm 101 which is engageable against enlargement 90 and in notch 90a or in enlargement 91 and notch 91a, at the extremes of raising and lowering movement of the frame to automatically disengage the pin 86 from the teeth 79 at both extremes, enabling

relative movement of the drums or parts adjustably mounting the wheel and free rotation of wheel 12 thereafter with drum 18 rotating with it. Lever 97 may be actuated by a draw element such as a cable 106 fastened to the same at one end and at 107 at the other end to the lever 76, the cable passing through a guide 108 on such lever. When the elevation of the frame 11 is to be varied, lever 97 is rocked in order to slide the arm 101 to rock lever 87 and engage the latch pin 86 with the teeth 79, whereupon the axle 72 will swing to the desired extent on the pin 74, following which, the lever 97 is released, slide 100 is restored by spring 103 to normal position and the arcuate rod 89 again restores the latch 83 out of engagement with adjacent teeth 79, the movement of the crank 94 having been accommodated in the slide 95 mounted on the turnable cap 93.

Various changes may be resorted to provided they fall within the spirit and scope of the appended claims.

I claim as my invention:

1. In mechanism of the class described, a drum, a drum concentric with the first-mentioned drum and relatively to which the first-mentioned drum

turns, pin means mounted by the second-mentioned drum, means on the first mentioned drum engageable by the pin means to cause the drums to rotate together, a transverse rod member capable of rocking adjustment, an element loose relatively to the drums, a crank on the rod member slidably connected to the element, and co-acting latch parts mounted by the crank and second-mentioned drum.

2. In mechanism of the class described, a drum, a drum concentric with the first-mentioned drum and relatively to which the first-mentioned drum turns, a lever pivoted on the second-mentioned drum, a pin on said lever, means on the first mentioned drum engageable by the pin to cause the drums to rotate together, a transverse rod member capable of rocking adjustment, an element loose relatively to the drums, a crank on the rod member radially slidably connected to the element, latching means on the crank coacting with said lever and operative to cause the pin to secure the drums together at different adjustments, and means operable on the crank to control the latch means.

WILLIAM A. DOANE.
